CLAIM

The ornamental design for a chair, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view, showing my new design in a closed configuration and where color is an integral part of the design;

FIG. 2 is a rear perspective view of the chair of FIG. 1;

FIG. 3 is a side view of the chair of FIG. 1;

FIG. 4 is a top view of the chair of FIG. 1;

FIG. 5 is a side view of the chair of FIG. 1, from the same side as FIG. 3 but in an open configuration;

FIG. 6 is a perspective view of the chair of FIG. 1, in an open configuration; and,

FIG. 7 is a rear perspective view of the chair of FIG. 1, in an open configuration.

1 Claim, 7 Drawing Sheets
(7 of 7 Drawing Sheet(s) Filed in Color)
